(57) **CLAIM**

The ornamental design for a watch case as shown and described.

DESCRIPTION

FIG. 1 is a front, right side, bottom perspective view of a watch case showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front elevational view thereof, with a watchband attached.

The broken lines depict portions of the watch case that form no part of the claimed design. The broken lines in FIG. 8 are included for the purpose of illustrating the environmental structure and form no part of the claimed design.

1 Claim, 7 Drawing Sheets
